GUIDE DEVICE

Stevenson Findlater, McKeesport, Pa., assignor
to National Tube Company, a corporation of
New Jersey

Application September 12, 1936, Serial No. 100,536

2 Claims. (Cl. 80—51)

This invention relates to rolling mills, and more particularly to guide devices therefor.

In processing metal work-pieces in a rolling mill, and particularly that type of mill wherein the work-piece is rotated on its axis while being moved longitudinally thereof, as, for instance, in the manufacture of pipes and tubes it is very important that careful guidance be effected within close tolerances in order to prevent "whipping" which seriously impairs the results obtained. In view of the fact that the work-pieces in contemplation are of considerable length, the provision of numerous guides is necessary. These guides must be frequently changed to accommodate various sections that are to be rolled.

It is accordingly among the objects of the present invention to provide an improved guide device which is laterally adjustable to accommodate work-pieces which vary over a wide range as to section, or size, and one which reduces to a considerable extent the deleterious stresses imparted by the work-piece.

Another object is the provision of an improved device of the class described which may be easily and inexpensively installed on mills of existing design.

The foregoing and other objects will be apparent after referring more particularly to the drawings, in which:

Figure 1 is a plan of the apparatus of the invention.

Figure 2 is an end elevation on the line II—II of Figure 1.

Figure 3 is an enlarged elevation of a detail.

Figure 4 is a plan of the detail of Figure 3.

Referring more particularly to the drawings, the numerals 2 and 3 designate suitable side frame members which are disposed on the mill floor adjacent and in alignment with either the inlet or outlet end of a conventional rolling mill such as, for example, a tube-processing mill. The side frame members 2 and 3 carry a plurality of pairs of aligned bearings 4, each pair of which rotatably supports a shaft 5 that extends across

the vertical plane of the "pass line" of the mill at an angle of substantially 45 degrees below the horizontal plane of the "pass line". Each shaft 5 carries an outboard pinion 6 adjacent the side frame member 2. An elongated shaft 8 is rotatably carried by the side frame member 2 and has secured thereon a plurality of pinions 9, each of which engages a pinion 6 on one of the shafts 5, thus enabling the synchronous rotation of the latter. The elongated shaft 8 is rotated in any suitable manner. An eccentric disk

10 is secured to the mid-portion of each of the shafts 5 at a point immediately below the horizontal "pass line" of the mill. Each of these eccentric disks 10 is provided with a plurality of grooves 11 which are at substantially 45 degree angles with respect to their axes.

A semi-cylindrical guide trough 12 is mounted in each of the grooves 11 for guiding the work-pieces being processed in the mill. These guide troughs 12 are of gradually varying cross-sectional size and are provided with flared inlet ends 14. It will be readily understood by those skilled in the art that the troughs 12 may be of other than semi-cylindrical shape, depending, of course, upon the section of the work-piece being rolled. From the foregoing it will be seen that upon rotation of the elongated shaft 8 and consequent rotation of the shafts 5, the eccentric disks 10 will be rotated in such manner that different sized guide troughs 12 will be brought into longitudinal alignment with the "pass line" of the mill. That is to say, the guide troughs 12 are so constructed and arranged on successive eccentric members 10 as to provide the same size in any given alignment thereof, the size being simultaneously changed for all aligned troughs by rotation of the eccentric disks 10.

According to the foregoing construction and arrangement of elements it will be seen that the stresses imparted to the guide troughs 12 by the helically advancing work-piece along the "pass-line" of the mill will be communicated to the bearings 4 neither axially of the mill nor in a direction which is normal thereto. This not only reduces the deleterious effects of such stresses but also permits the disposition of the bearings 4 such that they will not be directly under the advancing work-piece and hence susceptible to injury accruing from the heat thereof or scale falling therefrom.

An elongated shaft 20 is rotatably mounted on the side frame member 2 and carries a plurality of laterally extending arms 22, each of which is adapted for disposal over one of the eccentric disks 10 for cooperation with its various guide troughs 12. The under side of the extended end of each of the laterally extending arms 22 is provided with a semi-cylindrical groove 23 in order to effectively cooperate with the various guide troughs 12. The elongated shaft 20 carries a rigidly connected crank-arm 24 which is connected to the connecting-rod of a conventionally constructed and operated air cylinder 25.

An elongated shaft 26 is rotatably mounted on the side frame member 3 and carries a plurality of

of rigidly connected crank-arms 27. These crank-arms 27 are connected by links 28 to conventional "kick-off" arms 29 which are pivotally supported intermediate their ends by brackets 30, the latter being mounted on the side frame 3. These "kick-off" arms 29 extend below the "pass line" of the mill and are grooved on their extended ends.

In operation, the shaft 8 is suitably rotated 10 to dispose the desired guide troughs 12 in alignment with the mill. The shaft 20 is partially rotated (by any suitable means) to position the laterally extending arms 22 over the guide troughs 12, whereby they cooperate with the latter to 15 confine the work-piece. After the work-piece has been processed, the laterally extending arms 22 are raised by partial rotation of the shaft 20; and the shaft 26 is partially rotated by a motor 31 driving through gears 32 and 33 to elevate 20 the laterally extending "kick-off" arms 29, whereby the work-piece is raised from the guide troughs and permitted to roll laterally therefrom.

While I have shown and described one specific embodiment of my invention, it will be understood 25 that I do not wish to be limited exactly thereto, since various modifications may be made

without departing from the scope of my invention, as defined by the following claims.

I claim:

1. A guide for metal working mills comprising at least one rotatable element having its axis 5 at an angle of approximately 45 degrees with respect to the pass line of said mill, said rotatable element having a plurality of different sized guide troughs on its periphery and disposed at an angle of approximately 45 degrees with respect to the axis of said rotatable element, each of said guide troughs being capable of movement into longitudinal alignment with the pass-line of said mill.

2. A guide for metal working mills comprising 15 a plurality of rotatable elements, each having its axis of rotation at an angle of approximately 45 degrees to the pass line of said mill, said rotatable elements having a plurality of different sized guide troughs on its periphery and disposed at 20 an angle of approximately 45 degrees with respect to the axis of said rotatable element, each of said guide troughs being capable of movement into longitudinal alignment with the pass-line of 25 said mill.

STEVENSON FINDLATER.
